(57) **CLAIM**

I claim the ornamental design for a home power station, substantially as shown and described.

DESCRIPTION

A portion of this document contains material to which a claim for copyright is made. The copyright owner does not object to the facsimile reproduction of the document.

FIG. 1.1 is a top view of a home power station in accordance to the present invention in a first configuration, where a removable wheel cart is attached;

FIG. 1.2 is a left view of the first configuration;

FIG. 1.3 is a right view of the first configuration;

FIG. 1.4 is front view of the first configuration;

FIG. 1.5 is back view of the first configuration, showing slide door closed;

FIG. 1.6 is a back view of the first configuration, showing slide door open;

FIG. 1.7 top perspective view of the first configuration;

FIG. 1.8 is a bottom perspective view of the first configuration;

FIG. 1.9 is a front perspective view of the first configuration;

FIG. 2.1 is a top view of a home power station in accordance with the present invention in a second configuration, where the removable wheel cart is not attached;

FIG. 2.2 is a left view of the second configuration;

FIG. 2.3 is a right view of the second configuration;

FIG. 2.4 is front view of the second configuration;

FIG. 2.5 is back view of the second configuration;

FIG. 2.6 top perspective view of the second configuration;

FIG. 2.7 is a bottom perspective view of the second configuration;

FIG. 2.8 is a front perspective view of the second configuration;

FIG. 3.1 is a top view of the wheel cart of FIG. 1, standing alone;

FIG. 3.2 is a bottom view of the wheel cart;

FIG. 3.3 is left side view of the wheel cart;

FIG. 3.4 is a right view of the wheel cart;

FIG. 3.5 is a front view of the wheel cart;

FIG. 3.6 is a back view of the wheel cart;

FIG. 3.7 is a top perspective view of the wheel cart;

FIG. 3.8 is a bottom perspective view of the wheel cart;

FIG. 3.9 is a front perspective view of the wheel cart.
